(57) **CLAIM**

The ornamental design for a plumbing fitting, as shown and described.

DESCRIPTION

FIG. 1 is a perspective view from above showing our new design of a plumbing fitting;

FIG. 2 is a top view thereof;

FIG. 3 is a left side view thereof, the right side view is a mirror image of the left side;

FIG. 4 is a bottom view thereof;

FIG. 5 is a front view thereof;

FIG. 6 is rear view thereof; and,

FIG. 7 is a cross-sectional view thereof, taken along line 7-7 in FIG. 2.

The broken line shown in the drawings depicts portions of the plumbing fitting that form no part of the claim.

The article is a plumbing outlet fitting that is attached to one or more ends of a piece of equipment such as, but not limited to, a pump, filter, or sterilizer.
